UNITED STATES PATENT OFFICE.

PETER J. LEYENDECKER, OF PHILADELPHIA, PENNSYLVANIA.

MEANS FOR SUPPORTING MATTRESSES ON BED-FRAMES.

No. 807,389.

Specification of Letters Patent.

Patented Dec. 12, 1905.

Application filed October 1, 1904. Serial No. 226,837.

To all whom it may concern:

Be it known that I, PETER J. LEYENDECKER, a citizen of the United States, residing in Philadelphia, Pennsylvania, have invented certain Improvements in Means for Supporting Mattresses on Bed-Frames, of which the following is a specification.

My invention relates to improvements in supporting structures for metallic mattresses; and it consists more particularly in a device whereby a folding mattress of the type described in an application for United States patent filed by me June 15, 1904, Serial No. 212,728, may be properly applied to and supported upon a metallic bed-frame of any of the forms commonly in use.

I attain my object as hereinafter set forth, reference being had to the accompanying drawings, in which—

20 Figure 1 is a plan view of a bed-frame, showing a spring-mattress in position thereon and illustrating the application thereto of my improved supporting means, a portion of the wire mattress proper being broken away in 25 order to more clearly illustrate the construction of the device. Fig. 2 is an enlarged end elevation, partly in section, of the device shown in Fig. 1; and Fig. 3 is a sectional elevation, also enlarged, taken on the line 3 3, 30 Fig. 1.

I have found that a serious objection to various types of folding mattresses, as well as to the ordinary forms of metallic mattresses, in which but a single frame is employed, is 35 due to the fact that said mattresses are not conveniently adaptable for use on the different constructions of metallic bed-frames commonly manufactured, and while my invention hereinafter described is particularly 40 applicable to that form of folding-mattress illustrated and claimed in my application above referred to it will be understood that it may be employed with advantage with other forms of folding or single-frame mattresses,

45 In the above drawings, A represents a metallic bed-frame of well-known construction, there being sufficient of this illustrated to show the arrangement of the parts of my invention relatively thereto. Said bed-frame includes at its corners posts a and a' , connected by side bars formed of angle-sections a^2 , the two posts a being connected to each other by a head-bar a^3 and the two posts a' being similarly connected by a foot-bar a^4 .

55 For supporting my improved folding mattress, or indeed any other form of mattress,

upon this structure I provide at each end of said structure a transverse angle-section B, supported by the side bars a^2 and held from moving transversely thereon by means of 60 lugs or projections b near its ends, which engage horizontal portions of said side bars, as indicated in Figs. 2 and 3.

The folding mattress which it is desired to support in the present instance consists of 65 two similar frames hinged together and having stretched on them a body C of woven wire or equivalent material. Each of these frames consists of two parallel angle-sections c , rigidly held apart by struts c' , formed of 70 pieces of tubular metal connected together and to said sections c by means of metallic sockets c^2 and c^3 . The sockets c^3 are riveted or bolted to the angle-sections c and rest upon the horizontal portion of the transverse angle-sections B, being held in position thereon by hook projections or lugs c^4 , which extend over the upwardly-projecting edges of 75 said sections B. These latter sections may be made of any length suitable for the bed-frame to which the particular mattress is applied, and it will be noted that with the construction of parts described and illustrated it is possible to fold one of the mattress-sections over upon the other without disarranging 80 the position of the mattress as a whole upon the frame, there being two of the sockets c^3 to each of the angle-sections c of the mattress-frame, so that each end of said frame is held to the transverse angle-section 85 B by two of the lugs c^4 . The mattress is therefore removably held in proper position upon the bed-frame when in position for use as well as when one part is folded upon the other to permit of cleaning underneath the 90 bed.

While I have illustrated a mattress made with woven wire, it is to be understood that my device may be equally well adapted to mattresses of other construction without departing from the invention.

I claim as my invention—

1. The combination with a bed-frame and a mattress having a supporting-frame, of a transverse bar or bars supported by said bed-frame but independent thereof, said mattress-frame having lugs placed to removably engage said transverse bar or bars and thereby hold the mattress in position, substantially as described.

2. The combination with a bed-frame having side members, of transverse bars con-

nected to said members, a mattress having a supporting-frame, and means at each end of said mattress constructed to removably engage said bars for maintaining the mattress in a fixed position relatively to the bed-frame, and means other than said mattress-maintaining means for supporting the mattress, substantially as described.

3. The combination of a bed-frame, a folding mattress, and bars for supporting said mattress on said frame, means for retaining the bars in position, means positively connecting the mattress to said bars for preventing relative movement of said parts, and means other than said connecting means for transferring the weight of the mattress to the supporting-bars, substantially as described.

4. The combination of a bed-frame, mattress-supporting bars carried by but movable independently upon said bed-frame, a folding mattress including frames hinged together, and projections on each end of said mattress-frames placed to engage said bars, substantially as described.

25 5. The combination of a bed-frame, a folding mattress including frames hinged together and each having at its ends a plurality of lugs, and angles on the bed-frame each having a substantially vertical flange for engagement with said lugs, whereby the mattress is maintained in its extended position, said angles being carried by but movable in-

dependently of said bed-frame, substantially as described.

6. The combination of a bed-frame having side members, angle-sections respectively at the head and foot of the frame and extending between said side members thereof, projections on said angle-sections engaging the side members, a mattress, and a frame therefor, including castings having hook-lugs placed to engage the edges of certain of the flanges of said angle-sections, substantially as described.

7. The combination of a bed-frame having side members, angle-sections respectively at the head and foot of the frame and extending between said side members thereof, projections on said angle-sections engaging the side members, a mattress and a frame therefor, including castings having hook-lugs placed to engage the edges of the vertical flanges of said angle-sections, said castings resting upon and being supported by the horizontal flanges of said angle-sections, substantially as described.

In testimony whereof I have signed my name to this specification in the presence of two subscribing witnesses.

PETER J. LEYENDECKER.
